SHOE SUPPORTS

William A. Barker, Leicester, England, assignor to United Shoe Machinery Corporation, Flemington, N.J., a corporation of New Jersey

Original application May 11, 1954, Ser. No. 429,070, now Patent No. 2,855,616, dated Oct. 14, 1958. Divided and this application Apr. 2, 1958, Ser. No. 725,865

5 Claims. (Cl. 12—127)

This invention relates to machines for operating on shoes, for shaping or leveling the bottoms thereof. More particularly, the invention relates to shoe supports and is illustrated as embodied in a machine of the type having a leveling tool, a shoe support, power operated means for effecting relative movements of the shoe support and the leveling tool in opposite directions lengthwise of a shoe on a support to cause the tool to operate progressively along the shoe bottom. Such a machine is illustrated and described in United States Letters Patent No. 2,855,616, granted October 14, 1958, in my name and of which this application is a division.

The shoe support comprises a toe support and a heel support adjustable relatively thereto to accommodate shoes of different sizes. It is desirable that the toe end of the shoe occupy a predetermined position relatively to the leveling tool and to insure the proper location of the shoe thereon and accordingly the proper positioning of the heel support, a gage is associated with the toe support. In accordance with an object of the invention the gage projects above the toe support for engagement by the toe end of the shoe and mechanism is provided for retracting the gage to avoid interference with the leveling tool during movement of the shoe support to carry the shoe beneath the leveling tool.

As a feature of the invention the heel support includes a last pin arranged to be received by the thimble of a last, the last pin being movable about an axis extending transversely of the last thereon so that the toe end of the last may be forced against the toe support and the last pin is also movable laterally about an axis extending lengthwise of the last to insure the proper relationship between the last and the toe support. During jacking of the shoe and movement of the last pin about its first-mentioned axis to force the toe end of the shoe against the toe support, the last pin is locked against further lateral movements preparatory to the leveling operation.

The above and other features of the invention including novel combinations of parts and details of construction will now be described by reference to the accompanying drawings and pointed out in the claims.

In the drawings,

Fig. 1 is a right elevation partly in section of one form of machine embodying the invention;

Fig. 2 is a right elevation partly in section illustrating one of the jacks in a forward position to receive a shoe;

Fig. 2a is a front elevation of the last pin mounting mechanism;

Fig. 2b is a side elevation with parts broken away of the last pin locking means;

Fig. 3 is a right elevation partly in section of mechanism by which the jack is actuated to carry the shoe forwardly and rearwardly beneath a leveling roll; and

Fig. 4 is a detail of a portion of the jack actuating mechanism, this view being taken at right angles to Fig. 3.

As illustrated herein the machine is provided with a pair of shoe supporting jacks one of which is shown in

2

Fig. 2, these jacks being arranged to swing rearwardly and forwardly to carry a shoe thereon beneath a leveling roll 270. Each jack comprises a toe support 146, a heel support 148 and a cone support 150.

The toe support 146 comprises a rubber pad 152 having a recess 154 shaped to conform to the toe portion of a shoe. The pad 152 is carried by a plate 156 having a pair of downwardly extending pins 158 fitting into holes in a block 160. The pad 152 and the plate 156 may be removed from the block 160 merely by lifting them whereby they are readily replaced if desired by an assembly having a toe pad with a differently shaped recess. The block 160 is carried for rocking movement whereby the pad accommodates itself to the toe end of the shoe.

15 For this purpose the block is mounted between side walls of an adjustable support 162 between the sides of which are journaled rolls 164 on which rests the curved bottom face of the block 160, so that the block and the toe pad may rock forwardly or rearwardly. The amount of rocking movement is limited by a pin 166 engageable with the sides of a recess 168 formed in the block 160. Engagement of this pin with the bottom of the recess prevents the block from being lifted from the adjustable support 162.

20 25 The lengthwise position of the shoe with respect to the toe support is controlled by a toe gage 170. This gage is carried for heightwise adjustment in a holder 172 which is pivotally mounted at 174 on the rearward end of a lever 176. This lever is pivoted on a pin 178 which

30 35 carries the rear block supporting roll 164 and has a forwardly extending arm 180 which is normally held by a spring 182 against a pin 184 carrying the forward block supporting roll 164. The toe gage holder 172 has a downwardly extending arm 185 carrying an adjustable stop screw 186 which is normally held in engagement with a jack post 188 by a torsion spring 190. It will be understood that by adjusting the stop screw 186 the position of the gage lengthwise of the toe support may be readily adjusted. At an opportune time at the beginning

40 45 of the cycle of operations of the machine the lever 176 is moved in a clockwise direction about the pivot 178 to move the toe gage 170 downwardly to avoid interference with the leveling roll as will be hereinafter explained.

The adjustable support 162 for the toe pad is mounted at the upper end of the jack post 188 for heightwise adjustment, the heightwise position of the support being controlled by a wedge 192 between the jack post and the adjustable support and arranged to be adjusted by a hand screw 194. The jack post 188 is mounted for rocking movements on a horizontally extending shaft 196 extending laterally of the machine near the front thereof. The jack post has a rearwardly extending arm 198 arranged to be connected to mechanism for rocking the jack during the leveling operation as will be described. The jack post also includes a downwardly extending arm 200 to which is pivotally connected a heel post 202.

50 55 For moving the toe gage 170 down at the beginning of the leveling operation the arm 185 of the support for the gage is connected by a chain or suitable flexible connection 276 passing around a guide pulley 278 with a lever 280 pivoted to an arm 254 of a lever 256 pivoted at 258 to the jack post 188. A spring 282 connected between the levers 280 and 256 maintains the chain 276 taut. The lever 256 has a downwardly extending arm 260 carrying a cam roll 262 arranged upon rearward swinging movement of the jack to engage a cam 264 secured to the frame of the machine.

50 55 60 65 70 75 80 85 90 95 Each of the jacks of the machine may assume a position at the end of a cycle of operations in which it is in a well forward position as shown in Fig. 2 to enable a hand operation to be performed on the shoe if desired or

each may be stopped in a more rearward position as shown in Fig. 1 in which the toe end of the shoe is adjacent to the leveling roll. With the jack in either of these positions a tension spring 266 connected to the upper arm of the lever 256 and to the jack post 188 holds the upper arm of the lever in a forward position against an adjustable stop screw 267 carried by the jack post.

If the jack is in its forwardmost position at the end of a cycle of operations it is moved back to the position shown in Fig. 1 by the operator before the machine is started. In this position the toe end of the sole of the shoe is located slightly ahead of the leveling roll 270 and the cam roll 262 (Fig. 2) on the lever 256 is in or nearly in engagement with a portion 272 of the fixed cam 264. Upon further movement of the jack by the power operation of the machine as described more fully in the above-noted Patent No. 2,855,616, engagement of the cam roll 262 with the inclined portion 272 of the cam causes the lever 256 to move in a clockwise direction as viewed in Fig. 2. This movement of the lever 256 causes the cone support 150 to be locked in its firm supporting position as fully set forth in said patent and also causes the toe gage 170 to be moved downwardly through the aforementioned connections against the action of the spring 182.

To assist the operator in moving the jack rearwardly from its forwardmost position into the position of Fig. 1, the weight of the jack is substantially balanced by a torsion spring 288 one end of which engages the jack and the other end of which engages an adjustable block 290 secured by a screw 292 to a member 294 mounted on the shaft 196. The member 294 has a rearwardly extending arm 296 engageable with a lug 286 on the frame of the machine. The block 290 and the member 294 have interengaging teeth to prevent relative slipping movement between them. The spring is so arranged that the jack as it moves forwardly tensions the spring and the extent of this tension is adjusted by varying the position of the block 290 on the member 294.

Carried by the upper end of the heel post for forward and rearward as well as lateral movements is a last pin 298 arranged to be received by the thimble in the heel end of a last. The last pin is mounted in a holder 300 carrying a rearwardly extending pin 302 rotatably mounted in a block 304 pivoted at 306 to the upper end portion of a block supporting post 308 mounted in the heel post 202. Thus the last pin can swing forwardly and rearwardly about the pin 306 and laterally about the axis of the pin 302. Slidably mounted in the holder 300 is a last supporting pin 310 arranged to engage the forward portion of the heel end of the last. The lower end of the last supporting pin 310 rests on the upper end of a pin 312 slidably mounted in the block 304, the arrangement being such that the last supporting pin 310 can move relatively to the pin 312 when the last pin 298 moves laterally about the axis of the pin 302.

The lower end of the last pin has an annular groove 314 engaged by a ball 316 in the last pin holder 300. The ball is held in the groove 314 by the last supporting pin 310 so that when the last supporting pin is withdrawn from the holder the last pin 298 may be withdrawn from the holder and replaced with a pin of the desired size. The lower end of the pin 312 rests on a face 318 of the block supporting post 308. The holder 300 is locked in its laterally tilted position by a plunger 320 the upper end of which has an arcuate toothed surface arranged to engage a correspondingly toothed surface on the lower face of the holder 300. The lower end of the plunger 320 is engaged by a cam 322 pivoted at 324 on a downwardly extending arm of the block 304. The cam 322 has a rearwardly extending arm pivotally connected to the upper end of a rod 326. Pivotally connected to the block 304 is the upper end of a downwardly extending rod 328, the lower portion of

which passes downwardly between the arms of a yoke member 330. The upper end portions of the arms of the yoke are pivoted on a horizontal spindle 332, secured in the rearwardly extending arms of a pair of last pin actuating levers 334, the yoke lying between these arms. The lower end of the rod 328 has connected to it a tension spring 336 the lower end of which is connected to the heel post 202. This spring urges the last pin 298 rearwardly into the position shown in Fig. 2. Surrounding the lower end of the rod 328 is a compression spring 338 the lower end of which rests on a block 340 adjustably supported by a nut 342 threaded on the lower end of the rod 328. Upon placing a last on the last pin 298, the toe end thereof is moved upwardly by the operator and swung over the toe rest 152 and placed thereon. During this movement of the toe end of the shoe the last pin is swung forwardly from the position shown in Fig. 2 causing the rod 328 to be raised and bringing the upper end of the compression spring 338 close to the undersurface of the yoke member 330. For a purpose to be described, the yoke member 330 may be swung rearwardly from above the spring 338 and held in this position or in the position shown in Fig. 2 by a spring plunger 344 in one of the arms of the yoke member engaging one of two recesses in the spindle 332.

The last pin actuating levers 334 are pivoted on pins 346 carried by upwardly extending lugs 348 located at opposite sides of the block supporting post 308. The lugs 348 are carried by a member 350 slidably mounted on the post 308. Pivoted to the forwardly extending arms of the levers 334 is the front end portion of an actuating link 352. A rear end portion of this link is pivotally connected to a rearwardly and upwardly extending arm of a hand lever 354 pivotally carried by a laterally extending pin 356 secured in the heel post 202. The actuating link 352 and the arm of the hand lever 354 form a toggle which with the hand lever in a raised position, as shown in Fig. 2, is broken and is straightened upon movement of the hand lever into the lowered position shown in Fig. 1. With the hand lever 354 in its raised position it extends upwardly and forwardly from the pin 356 and is provided at its forward end with a handle 358 arranged to be gripped by the operator.

Pivoted to the hand lever 354 and extending beneath the handle 358 is a latch lever 360 to which is pivoted one end of a latch rod 362. The other end of the latch rod is guided by a hole through a stud 364 pivoted in the hand lever 354. The lower end of the rod 362 is normally held in a recess in a block 366 secured to the heel post 202 by a tension spring 368 connected to the latch lever 360 and the hand lever 354. By moving the latch lever 360 upwardly the rod 362 is withdrawn from the recess and upon movement of the hand lever 354 to its lowered position the end of the rod rides off the block 366 and is moved by the tension spring beneath the block to lock the hand lever in its lowered position. At this time a shoulder on the rod engages an arcuate face of the block to limit the movement of the rod beneath the block. The stud 364 passes through an arcuate slot 370 in the block 366 and limits up and down movement of the hand lever 354.

Pivoted to the hand lever 354 is the front end of a link 372 the rear end of which is pivoted to the upper end of an arm 374 of a control lever 376. This control lever is pivoted on a pin 378 in the heel post 202 and has a downwardly extending arm the lower end of which is in the form of two arcuate faces 380, 382 located at different distances from the pivot 378 and joined by an inclined face. Also pivoted on the pin 378 is a downwardly extending ratchet lever 384 provided at its lower end with rearwardly facing ratchet teeth 386. Beneath the arms of the controlling and ratchet levers is a spring detent 388 arranged to be engaged either by the arcuate face 380 of the controlling lever or by the ratchet teeth. The ratchet lever is provided with a rearwardly extend-

ing arm 390 engageable with a block 392 carried by the sliding member 350, and is so held by a tension spring 394.

With the parts positioned as illustrated in Fig. 2, the last engaging members on the heel post are in positions to receive a last and shoe. In placing the shoe on the jack, the thimble is placed over the last pin and the toe of the shoe is lifted so that it can be placed on the toe rest. This causes the last pin to be swung forwardly against the tension of the aforementioned spring 336, lifting the rod 328 and with it the spring 338 until the spring is just below the yoke member 330. With the last and shoe supported on the heel pin and on the toe rest, the hand lever 354 is moved down by the operator thus straightening the toggle formed by the hand lever and the link 352 causing the actuating levers 334 to turn about their pivotal connection 346 to the sliding member 350 until the resistance offered by the shoe through the last pin and rod 328 causes the actuating levers to turn about their pivotal connection to the yoke member 330 thereby raising the sliding member 350. As this member rises, the block 392 thereon raises the arm 390, swinging the ratchet lever 384 in a counterclockwise direction, the teeth 386 moving past the detent 388 which is being held down by the face 380 of the controlling lever 376. Before the toggle formed by the hand lever and the link 352 is fully straightened, the controlling lever 376 which has been moving in a counterclockwise direction as the hand lever has been moved down, presents the face 380 to the detent 388 allowing the detent to engage one of the ratchet teeth to lock the ratchet lever 384 against further counterclockwise movement and thus to lock the sliding member 350 against further upward movement. During the last part of the downward movement of the hand lever 354 after the sliding member has been locked, the toggle straightens and the actuating levers 334 move about their pivot 346 on the sliding member 350 and through the rod 328 and the spring 338 move the last pin rearwardly to press the toe end of the shoe firmly against the toe rest.

When the hand lever reaches its lowest position the operator releases the latch lever 360 whereupon the latch rod 362 locks the hand lever and the parts controlled thereby in this position during the leveling operation. At the completion of the leveling operation the operator grips the latch lever 360 to release the latch rod and raises the hand lever to return the parts to their starting positions.

The lower end of the rod 326 which controls the cam 322 by which the last pin holder is locked against lateral tipping movements has at its lower end a slot through which passes a pin 396 carried by an arm 398 pivoted at 400 to the link 352. The arm 398 is connected by a spring 402 to the link 352. This spring normally holds a portion 404 of the arm 398 against a face on the link 352. Upon downward movement of the hand lever 354, the toggle formed by the hand lever and the link 352 is straightened and during this straightening movement the pin 396 moves into engagement with the lower end of the slot in the rod 326 and then moves the rod downwardly to move the cam member 322 in a clockwise direction moving the plunger 320 upwardly to engage the toothed arcuate face on the last pin holder thus locking the holder against lateral movement. Following this locking of the last pin holder the arm 398 is permitted to move about its pivot against the action of the spring 402 without causing damage to the parts which have been locked against further movement.

With the parts in the positions shown in Fig. 2, the last supporting pin 310 is in a raised position. Upon swinging the last pin 298 forwardly about its pivot 306 as the toe portion of the last is raised by the operator, the face 318 upon which the lower end of the pin 312 rests permits this pin and consequently the last supporting pin 310 to be pressed down by the last as the last is

placed over the last pin by the operator and the last supporting pin 310 determines the heightwise position of the last on the pin 298. Upon downward movement of the hand lever 354 to force the toe end of the lasted shoe against the toe rest 146, the last pin 298 swings rearwardly and the pin 312 rides up the face 318 to press the last supporting pin 310 against the last firmly to support the heel end portion of the last against the pressure of the leveling roll.

- 10 For accommodating shoes of different sizes, the heel post 202 is adjustable toward and away from the jack post 188. For this purpose, the posts are connected by a screw 406 threaded through a block 408 on the jack post and passing through a block 410 on the heel post, 15 the screw carrying collars at opposite sides of the block 410 to prevent lengthwise movement of the screw therethrough. The forward end of the screw carries a handle 412 by which the screw may be turned to move the heel post toward or away from the jack post.
- 20 It may be desirable to employ a stirrup or saddle 414 (Fig. 1) to hold the lasted shoe in position on the jack. In such case the yoke member 330 (Fig. 2) is swung rearwardly from above the spring 338 to free the last pin for swinging movement about the pivot 306. The stirrup 25 414 may be detachably connected to the last pin actuating levers 334 by yielding connections similar to those illustrated and described in Letters Patent of the United States No. 2,073,005, granted March 9, 1937, in the name of Andrew Eppler. Upon removal of the stirrup 30 414 the yielding connections may be held in inoperative positions by a latch 416 (Fig. 2). The stirrup disclosed herein does not cover the entire shoe bottom as in the aforementioned patent but covers only the shank portion of the shoe. A stirrup of such width is more effective 35 to hold the shank portion of the shoe bottom against the last than one which covers the forepart and heel seat. The mechanism operates in the manner above described except that the saddle is pulled firmly against the shoe to press the toe end of the shoe against the toe rest 40 instead of relying upon rearward tipping movement of the last pin.
- For connecting the jack to power operated mechanism by which forward and rearward movements of the jack are effected during the leveling operation, the rearwardly 45 extending arm 198 is provided with a hole 418 to receive an end portion of a bolt 420 (Figs. 3 and 4) slidably mounted in a jack rocking arm 422 which is pivoted on the shaft 196 by which the jack post 188 is carried, the arm extending rearwardly from the shaft at one side of 50 the rearwardly extending arm 198. The bolt 420 has extending upwardly into it a recess 424 which receives the upper ball-shaped end of a stud 426 which passes through an opening in the jack rocking arm 422 and is secured in the upper end of an arm 428 of an actuating lever 430 pivoted on a forwardly and rearwardly extending spindle 432 in the jack rocking arm 422. The bolt 420 is urged in a direction to enter the hole 418 in the arm 198 by a compression spring 434 housed within the arm 422 and engaging the inner end of the bolt 420.
- 60 The bolt actuating lever 430 has a laterally extending arm 436 which is normally held against an adjustable screw 438 in the jack rocking arm 422 by the spring 434. Pivoted to the outer end of the laterally extending arm 436 is an upwardly extending bar 440 which passes 65 through an opening in the outer end portion of a trip arm 442. This trip arm is pivoted on a pin 444 carried by an upwardly projecting bracket of the arm 422. A tension spring 446 connects a downwardly extending arm 448 of the trip arm 442 to the bar 440 urging the arm 70 448 toward a stop pin 450 in the jack rocking arm and the side face of the bar 440 toward a roll 452 on the jack rocking arm 422. Secured to the underside of the trip arm 442 is a block 454 arranged to engage the upper end of a block 456 on the side of the bar 440 during the 75 operation of the machine on a shoe.

Upon forward movement of the jack at the conclusion of a leveling operation toward its loading position the rearwardly extending arm 198 and the jack rocking arm 422 are moving upwardly whereupon the trip arm 442 moves into engagement with a screw 458 carried by a bracket 460 in the upper portion of the machine frame so that the trip arm moves downwardly about its pivot 444. During this movement the block 454 engages the upper end of the block 456 on the bar 440 moving the bar downwardly and rocking the bolt actuating lever 430 in a clockwise direction, as seen in Fig. 4, to withdraw the bolt 420 from the arm 198 of the jack post. As soon as the bolt is withdrawn from the jack post the jack moves forwardly by gravity to its forwardmost position until a leather-covered lug 284 (Fig. 2) on the jack post 188 engages the lugs 286 on the machine frame. The arm 422 continues to move upwardly and the bar 440 moves further downwardly whereupon a cam 462 on the side of the bar 440 engages the roll 452 moving the bar about its pivot against the action of the spring 446 to move the block 456 on the bar from beneath the block 454 on the trip arm 442. The spring 434 thereupon pushes the bolt 420 outwardly and the bar 440 upwardly into the position shown in Fig. 4. Upon downward movement of the jack rocking arm 422 at the beginning of the next cycle of operations of the machine the outer end of the trip arm 442 is raised by the spring 446 and the block 456 on the bar 440 snaps under the block 454 on the trip arm 442.

The rearwardly extending arm 198 has an inclined cam face 439 (Fig. 4) which engages the outer end of the bolt 420 and pushes the bolt inwardly against the action of the spring 434 upon movement of the jack rearwardly from its forwardmost position. This action continues until the hole 418 in the arm 198 arrives opposite to the bolt whereupon the bolt snaps into the hole thus connecting the jack to the power operating mechanism. Carried in the rear end of the arm 198 is a vertically movable plunger 441 the lower end of which engages a lug 443 on the jack rocking arm 422 during this rearward movement of the jack, causing upward movement of the plunger and stressing of a leaf spring 445 secured to the arm 198. This spring provides a force to start movement of the jack forwardly at the end of the leveling operation upon withdrawal of the bolt 420 in the jack actuating arm from the hole 418 in the jack.

Should it be desired to arrest the forward motion of the jack in the position shown in Fig. 2, the bracket 460, which is pivoted to a bracket on the machine frame is swung out of the way to an inoperative position so that the trip arm 442 is not operated to withdraw the bolt 420 to release the jack for forward movement beyond the position shown in Fig. 1. Thus the bolt 420 remains in engagement with the jack rocking arm at all times until the bracket 460 is returned to its operative position.

For rocking the jacks in the leveling operation each jack rocking arm 422 has a forwardly and rearwardly extending arcuate slot 468 in which is adjustably mounted a block 470 pivotally connected to the upper end portion of one of a pair of actuating links 472 there being one link for each jack. The lower ends of the links 472 are pivoted to a jack operating lever 474. The forward end of this lever is pivoted to the upper end of a connecting rod 476 the lower end of which surrounds an eccentric 478 carried by a shaft 480 journaled in bearings in a housing 120 (Fig. 1). The shaft 480 has secured to it a worm gear 494 driven by a worm 486 on a drive shaft 10, and consequently rotates continuously during each cycle of operation of the machine. The rear end of the jack actuating lever 474 is pivoted to the front end portion of a guiding link 488 which is pivoted at its rear end to a bracket 490 on the machine frame. The jack actuating lever 474 carries a cam roll 492 which rides in a cam groove 494 in a cam 496 car-

ried by a cam shaft 130. This shaft carries a gear 498 driven from a gear 500 carried by the shaft 480. The forward and rearward movements of the jack are thus controlled by the vertical movements of the link 472 which is in turn controlled by the conjoint action of the eccentric 478 and the cam roll 492 riding in the groove 494 of the cam 496.

Provision is made for adjusting the block 470 along the slot 468 for varying the jack motion automatically according to the size setting of the jack as well as manually independent of the size adjustment of the jack in a manner fully described in the above-noted Patent No. 2,855,616.

Having thus described my invention, what I claim as new and desire to secure by Letters Patent of the United States is:

1. In a leveling machine having a leveling tool, a jack for carrying a shoe forwardly and rearwardly beneath the leveling tool to cause the tool to operate progressively along the bottom of the shoe on the jack, said jack comprising a toe support, a heel support adjustable relatively to said toe support in accordance with the size of the shoe to be operated upon, a gage associated with and projecting above said toe support for engagement with the toe end of the shoe to assist in properly positioning the shoe lengthwise on the jack, means mounting said gage for adjustment lengthwise of the toe support, and automatic means operable prior to engagement of the tool with the shoe bottom for retracting the gage to avoid interference with the leveling tool.

2. In a leveling machine having a leveling tool, a jack for carrying a shoe forwardly and rearwardly beneath the leveling tool to cause the tool to operate progressively along the bottom of the shoe on the jack, said jack comprising a toe support, a heel support adjustable relatively to said toe support in accordance with the size of the shoe to be operated upon, a gage associated with and projecting above said toe support for engagement with the toe end of the shoe to assist in properly positioning the shoe lengthwise on the jack, and means operative in response to movement of the jack to carry the shoe beneath the leveling tool for retracting the gage to avoid interference with the leveling tool.

3. In a leveling machine having a leveling tool, a jack for carrying a shoe forwardly and rearwardly beneath the leveling tool to cause the tool to operate progressively along the bottom of the shoe on the jack, said jack comprising a toe support, a heel support adjustable relatively to said toe support in accordance with the size of the shoe to be operated upon, a gage associated with and projecting above said toe support for engagement with the toe end of the shoe to assist in properly positioning the shoe lengthwise on the jack, means operative in response to movement of the jack to carry the shoe beneath the leveling tool for retracting the gage to avoid interference with the leveling tool, and means mounting said gage for adjustment lengthwise of the toe support.

4. In a leveling machine having a leveling tool, a jack for carrying a shoe forwardly and rearwardly beneath the leveling tool to cause the tool to operate progressively along the bottom of the shoe on the jack, said jack comprising a toe support, a heel support adjustable relatively to said toe support in accordance with the size of the shoe to be operated upon, a gage associated with and projecting above said toe support for engagement with the toe end of the shoe to assist in properly positioning the shoe lengthwise on the jack, said jack being located in a predetermined position forwardly of the leveling tool prior to commencement of the leveling operation, power operated means for moving the jack rearwardly, and means operative at the beginning of said movement of the jack for depressing the gage below the shoe bottom to avoid interference with the leveling tool.

5. In a leveling machine having a leveling tool, a jack for carrying a shoe forwardly and rearwardly beneath the leveling tool to cause the tool to operate progressively along the bottom of the shoe on the jack, said jack comprising a toe support and a heel support, said heel support including a last pin arranged to be received by the thimble in the heel end of a last, means mounting said last pin for movement lengthwise and laterally of a shoe thereon, means for moving said last pin toe-

wardly of a shoe thereon to force the toe end of the shoe into firm engagement with the toe support, and means operative upon such movement of the last pin for locking the pin against lateral movement.
